LOOSE LEAF BINDER

Adolph G. Lotter, Milwaukee, Wis., assignor to
Stationers Loose Leaf Company, Milwaukee,
Wis., a corporation of Wisconsin

Application September 19, 1932
Serial No. 633,809

13 Claims. (Cl. 129—9)

This invention relates to certain new and useful improvements in loose leaf binders of the type commonly used in connection with visible record systems in which the leaves are so arranged in the binder that their lower and upper edges are stepped to permit data on the upper portion of the leaves to be visible at all times.

In such systems, it is frequently necessary to insert and remove leaves from the book, in which case it is necessary to shift some of the leaves to maintain their stepped relationship.

Numerous devices for accomplishing this result have been proposed, but these are either expensive to manufacture or do not provide the desired flexibility in the insertion or removal of the leaves and, therefore, this invention contemplates as an object the provision of an improved binder for use with visible record systems, which has increased flexibility as to its ability to shift one or more leaves in either direction to accommodate the removal or insertion of other leaves.

Another object of this invention is to provide simplified means for effecting sidewise shifting of the movable units carrying the impaling prong sections.

More specifically, it is an object of this invention to provide common means for locking the shiftable sections carrying the impaling prongs, against separation and for imparting the desired sidewise motion thereto.

And a further object of this invention resides in the provision of a novel latch carried by the longitudinally shiftable locking bar of the binder for releasably securing the locking bar against its longitudinal shifting.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a top plan view of a binder embodying this invention with the covers and leaves in open position;

Figure 2 is a top plan view of the binder back with the covers and leaves removed and with the

impaling prongs separated and shifted to staggered position, and with portions thereof broken away and in section;

Figure 3 is a bottom view of the prong-shifting mechanism forming part of the binder back, with the covers removed;

Figure 4 is a longitudinal section view taken through Fig. 1, on the plane of the line 4—4; and

Figure 5 is a cross-sectional view taken through Fig. 1, on the plane of the line 5—5.

Referring now more particularly to the accompanying drawings in which like numerals indicate like parts throughout the several views, the numeral 5 indicates generally the back of a loose leaf binder constructed in accordance with this invention. Covers 6 and 7 are hingedly connected with the back.

The back 5 of the binder is a composite structure built up on a main supporting plate 8 whose opposite ends are provided with inturned flanges 9 and 10 overlying the plate in spaced relation thereto. The side marginal edges of the supporting plate have hinge connections 11 for the attachment of the covers 6 and 7, as best illustrated in Fig. 5.

Overlying the inner face of the supporting plate are two prong-carrying, sidewise shiftable, plates 12 and 13. Both plates are of a thickness to be snugly confined between the inturned flanges 9 and 10 and the supporting plate proper, and the plate 12 is of a length substantially equal to the distance between the upstanding portions of the flanges 9 and 10. The plate 13 is of less length to permit longitudinal shifting thereof, as will be later described.

Both plates 12 and 13 have substantially semicircular impaling prongs 14 fixed thereto. The prongs 14 have their inner ends securely anchored to their respective plates and have their outer ends provided for inter-engagement so as to form complete binder rings when the plates 12 and 13 are brought into abutting relationship.

The prong-carrying plates 12 and 13 are guided for sidewise shifting toward and away from each other by the engagement of studs in the form of rivets carried by the plates and engaging in transverse slots formed in the main supporting plate.

The plate 12 has studs 15 riveted thereto to pass through elongated transverse slots 16 formed in the main supporting plate. These slots are of a length to accommodate the desired sidewise shifting of the plate 12.

The plate 13 has studs 17 riveted to it, to be receivable in either one of a pair of adjacent

110

elongated slots 18 or 19. These slots 18 and 19 are located directly opposite the slots 16 and are of the same length as the slots 16 to afford the same degree of sidewise shifting to the plate 13 as is permitted the plate 12.

As hereinbefore noted, the plate 12 has only a sidewise shifting movement whereas the plate 13 has both a sidewise and a longitudinal shifting motion so as to permit the prongs carried by the plates to be separated and staggered as is necessary in visible record binders. For this reason, the two guiding slots 18 and 19 must be provided for the plate 13, and to permit the studs 17 to be engaged in either slot, they are connected 15 as at 20.

As will be readily apparent from Fig. 2, when the studs 17 of the plate 13 are in the slots 18, the plates 12 and 13 are shiftable toward and away from each other with their prongs in line, 20 but when the studs 17 are in the slots 19, the prongs of the plates will be staggered.

The sidewise shifting of the prong-carrying plates 12 and 13 is effected simultaneously by longitudinal motion imparted to a locking bar 25 indicated generally by the numeral 21.

This locking bar is in the form of a plate of approximately the width of the main supporting plate and of a length somewhat shorter than the main supporting plate. It is in flat juxtaposition 30 to the undersurface of the main supporting plate and is held assembled therewith by the studs 15 and 17 which are carried by the prong plates 12 and 13. These studs 15 and 17 extend beneath the main supporting plate to project through cam 35 slots 22 and 23 respectively in the shifting bar and have enlarged heads 24 of greater diameter than the width of the cam slots to thus hold the shifter plate against displacement. Inasmuch as the studs 15 and 17 are securely riveted to 40 the plates 12 and 13, respectively, it follows that they serve to maintain the entire structure assembled.

The shifter plate is firmly held against any but longitudinal motion by studs 25 which have 45 one end riveted securely to the main supporting plate and have their other ends projected downwardly to extend through elongated longitudinal slots 26 in the shifter plate to be riveted to an enclosing or finishing member 27. This member 50 27 is provided merely as an enclosure for the mechanism and as clearly shown in Figs. 4 and 5, has its marginal edges flanged as at 28 to lie closely adjacent the covers 6 and 7 and provide a neat appearance.

Both cam slots 22 and 23 have portions 55 parallel with each other and the longitudinal axis of the binder back to afford means for locking the prong-carrying plates against separation. From these straight portions the cam 60 slots 22 and 23 have portions 31 diverging outwardly and away from each other so that upon longitudinal shifting of the plate 21, sidewise motion will be simultaneously imparted to both plates 12 and 13 through the medium of studs 15 and 17.

It is observed that the studs 17 of the plate 13, when in their positions aligned with the slots 19 at which the staggered relationship of the prongs exists, are located at the juncture of the straight and inclined portions 30 and 31 of their respective cam slots 23, and to accommodate the shifting of the plate 21 in this condition, the cam slots 23 have a second straight portion 32 extending from their opposite ends in parallel relationship to their portions 30. Into these sec-

ond straight portions 32, the studs 17 move when the shifter plate 21 is actuated to separate the prong-carrying plates when the plate 13 has been shifted to stagger the prongs.

Longitudinal shifting of the prong-carrying plate 13 can be effected only when the plates 12 and 13 have been separated, by reason of the fact that the studs 17 must be aligned with the longitudinal passage 20 connecting the slots 18 and 19 to permit such shifting. Longitudinal shifting of the plate 13 is further precluded by the engagement of a handle 33 fixed to the plate 13, in one or the other of two notches 34 formed in the inturned flange 10.

Yieldable means are also provided to restrain accidental shifting of the plate 13 from one position to the other. This means comprises a spring finger 35 riveted at one end to the upper face of the plate 13 and carrying at its other end a detent 36 which projects downwardly through an opening in the plate 13 to engage in one or the other of two transverse slots 37 formed in the main supporting plate 8.

At the end of the shifter plate 21 adjacent the handle 33, a finger-engaging portion 38 projects upwardly. This finger-engaging portion carries a spring latch indicated generally by the numeral 39 and which is operative to lock the binder against accidental opening.

The spring latch 39 consists of a substantially 105 right-angular member 40 hingedly connected as at 41 with the actuator 38 and yieldably urged by means of a torsion spring 42 mounted on the hinge, to a position engaging its latch 43 in an opening 44 formed in the inturned flange 10. The 110 latch 43 is provided by one end of the right-angular member 40 and its other end projects up from the hinged connection 41 to lie alongside the actuator 38 so that disengagement of the latch is readily accomplished by the normal application of force to pull out the shifter plate.

From the foregoing description taken in connection with the accompanying drawings, it will be readily apparent to those skilled in the art that this invention affords a mechanically simple and sturdy construction for visible record binders which is particularly characterized by the provision of common means for locking the prong-carrying sections against separation and also effecting the desired sidewise shifting there- 125 of while the prongs are aligned or in staggered relation.

What I claim as my invention is:

1. In a loose leaf binder adapted for use with visible record systems, two series of impaling prongs with their ends normally engaged to form binder rings, means for mounting and guiding the series of impaling prongs for movement away from each other to permit removal or addition of record leaves, common means to secure the impaling prongs against movement away from each other and for actuating their mounting and guiding means to separate the prongs, and means to shift one series of impaling prongs to stagger the prongs of the two series.

2. In a loose leaf binder adapted for use with visible record systems, two series of impaling prongs with their ends normally engaged to form binder rings, means to mount and guide the series of impaling prongs for movement away from each other to permit removal or addition of record leaves, said mounting and guiding means of one series being longitudinally shiftable to stagger the impaling prongs of the second series, and longitudinally shiftable means to move both series

of impaling prongs toward and away from each other with the longitudinally shiftable mounting and guiding means of said one series in either position.

5. 3. In a loose leaf binder adapted to contain record leaves for visible record systems, two series of impaling prongs with their ends normally engaging to form binding rings, mounting means for the impaling prongs movable toward and away from each other, one of said mounting means being longitudinally shiftable to enable the prongs carried thereby to be moved into staggered relation with respect to the prongs of the other series, and longitudinally shiftable means operable to simultaneously move the mounting means of both series toward and away from each other with the prongs aligned or in staggered relationship.

10. 4. In a loose leaf binder of the character described, a stationary mounting member, a pair of prong-carrying members, impaling prongs carried by said members with their ends normally engaging to form binding rings, said prong-carrying members being shiftable on said mounting member toward and away from each other to enable the impaling prongs to be separated, and one of said prong-carrying members being shiftable longitudinally to stagger the prongs of the two members, a shifter member longitudinally slideable on the said mounting member, and cooperating means carried by the prong-carrying members and the shifter member to simultaneously shift the members laterally toward and away from each other upon longitudinal movement of the shifter member.

15. 5. In a loose leaf binder for visible record systems, a stationary main supporting plate, a pair of prong-carrying plates slideable transversely over the main supporting plate toward and away from each other, a series of impaling prongs carried by each slideable plate and adapted to have their ends engaged to form binder rings when the plates are adjacent, one of said plates being longitudinally shiftable on the main supporting plate to enable its series of prongs to be staggered with respect to the prongs of the other series, studs carried by the prong-carrying plates and received in guideways formed in the main supporting plate to positively guide the movements of the prong-carrying plates on the supporting plate, and an actuator longitudinally shiftable beneath the main supporting plate and engaging the studs to simultaneously shift the prong-carrying plates transversely toward and away from each other with the longitudinally shiftable prong-carrying plate in either position.

20. 6. In a loose leaf binder for visible record systems, a flat supporting plate, a pair of prong-carrying plates slideable transversely over the flat supporting plate into and out of abutting relation, a series of impaling prongs carried by each prong-carrying plate and adapted to have their ends engaged to form binder rings when the prong-carrying plates are in abutting relation, studs carried by the prong-carrying plates and received in slots in the supporting plate to guide the motion of the prong-carrying plates, the slot receiving the stud of one prong-carrying plate being arranged to limit the movement of said prong-carrying plate to a transverse motion and the slot for the stud of the other prong-carrying plate being substantially U-shaped to enable said second prong-carrying plate to be moved longitudinally to stagger its prongs with respect to the prongs of the other plate and to enable transverse motion of said second plate with its prongs in either stag-

gered or aligned position with respect to the prongs of the said first-mentioned plate, and means underlying the supporting plate and shiftable longitudinally to move the prong-carrying plates simultaneously into and out of abutting relation with said second-mentioned prong-carrying plate in either position of longitudinal adjustment.

25. 7. In a loose leaf binder for visible record systems, a main supporting plate, a pair of prong-carrying plates mounted on said main supporting plate for movement into and out of abutting relation, a series of prongs carried by each of said plates and adapted to have their ends engaged to form binder rings when the prong-carrying plates are in abutting relation, a stud carried by each prong-carrying plate and received in a slot formed in the main supporting plate, the slot for the stud of one plate being shaped to limit the movement of its plate to a transverse motion and the slot for the stud of the other plate being arranged to permit longitudinal motion of its prong-carrying plate to stagger the impaling prongs carried thereby with respect to the prongs of the other plate and also to permit transverse motion of said second prong-carrying plate in either of its positions of longitudinal adjustment to enable the two pairs of impaling prongs to be brought into juxtaposition when aligned or staggered, an actuator longitudinally movable beneath the main supporting plate, and cam means on said actuator engaging the studs to simultaneously shift the prong-carrying plates into and out of abutting relation.

30. 8. In a loose leaf binder, two series of impaling prongs with their ends normally engaged to form binder rings, means for mounting and guiding the series of impaling prongs for movement away from each other to permit removal or addition of record leaves, a longitudinally shiftable actuator adapted to secure the impaling prongs against movement away from each other and for actuating the mounting and guiding means to separate the prongs, a handle for said actuator, and a spring latch carried by said actuator and having a releasing element overlying the handle, said spring latch engaging a stationary part to normally restrain movement of the actuator and being releasable by the application of pressure to its releasing element overlying the handle, effected by the exertion of normal pressure onto the handle to shift the actuator.

35. 9. In a binder for visible record systems, a flat supporting plate, a pair of flat prong-carrying plates overlying one face of the supporting plate and adapted for movement toward and away from each other, a series of impaling prongs carried by each prong-carrying plate and arranged to have their ends normally engaged to form binder rings, said series of impaling prongs being separable by movement of the prong-carrying plates away from each other, a longitudinally shiftable actuator underlying the flat supporting plate, co-operating means carried by the prong-carrying plates and the actuator to simultaneously impart movement to both prong-carrying plates toward and away from each other upon longitudinal reciprocation of the actuator, one of said prong-carrying plates being longitudinally shiftable to enable its series of impaling prongs to be moved into staggered relation with respect to the prongs of the other series, and means to prevent such longitudinal shifting of said prong-carrying plate except when the prong-carrying

plates have been moved by the actuator to their separated positions.

10. In a binder for visible record systems, a flat supporting plate, a pair of flat prong-carrying plates overlying one face of the supporting plate and adapted for movement toward and away from each other, a series of impaling prongs carried by each prong-carrying plate and arranged to have their ends normally engaged to form binder rings, said series of impaling prongs being separable by movement of the prong-carrying plates away from each other, a longitudinally shiftable actuator underlying the flat supporting plate, cooperating means carried by the prong-carrying plates and the actuator to simultaneously impart movement to both prong-carrying plates toward and away from each other upon longitudinal reciprocation of the actuator, one of said prong-carrying plates being longitudinally shiftable to enable its series of impaling prongs to be moved into staggered relation with respect to the prongs of the other series, means to prevent such longitudinal shifting of said prong-carrying plate except when the prong-carrying plates have been moved by the actuator to their separated positions, and yieldable means to restrain longitudinal shifting of said prong-carrying plate at all times.
11. In a loose leaf binder, two series of impaling prongs with their ends normally engaged to form binder rings, means for mounting and guiding the series of impaling prongs for movement away from each other to permit removal or addi-

tion of record leaves, a longitudinally shiftable actuator adapted to secure the impaling prongs against movement away from each other and to actuate the mounting and guiding means to separate the prongs, and locking means to prevent actuation of said actuator.

12. In a loose leaf binder, two series of impaling prongs with their ends normally engaged to form binder rings, means for mounting and guiding the series of impaling prongs for movement away from each other to permit removal or addition of record leaves, a longitudinally shiftable actuator adapted to secure the impaling prongs against movement away from each other and to actuate the mounting and guiding means to separate the prongs, and a releasable latch having connection with the actuator and a fixed part to normally releasably lock the actuator against actuation.

13. In a loose leaf binder, two series of impaling prongs with their ends normally engaged to form binder rings, means for mounting and guiding the series of impaling prongs for movement away from each other to permit removal or addition of record leaves, a longitudinally shiftable actuator adapted to secure the impaling prongs against movement away from each other and to actuate the mounting and guiding means to separate the prongs, and a spring latch carried by the actuator and engageable with a fixed part to normally secure the actuator against accidental actuation.
